APPARATUS FOR CONDITIONING METAL BODIES

Alfred J. Miller, Garwood, James H. Bucknam, Cranford, and William C. Weidner, Grantwood, N. J., assignors to The Linde Air Products Company, a corporation of Ohio

Application August 10, 1940, Serial No. 352,042

26 Claims. (Cl. 266—23)

This invention relates to the art of conditioning surfaces of metal bodies and more particularly to apparatus for thermo-chemically removing a layer of metal from longitudinal surfaces of a ferrous metal body such as a steel bar, billet, bloom, slab, or the like and to apparatus for removing scale from such surfaces.

In the casting of steel ingots and during the hot rolling of steel, defects such as scale, cracks, seams, and the like form on and in the surface of a steel body and in turn cause imperfections in the finished rolled products. In order to reduce the number of rejections of the finished products, it is desirable to condition such steel bodies to remove such defects. Apparatus has heretofore been employed for conditioning the longitudinal surfaces of ferrous metal bodies either when cold or preferably when at an elevated temperature and moving along a roll table conveyor from one roll stand to another, such as are commonly employed in steel mills. But such prior apparatus has only been adapted to condition or desurface the longitudinal surfaces of a steel shape of one particular cross-sectional size so that considerable time is lost whenever either the width or the thickness of successive steel shapes moving along the roll table changes.

The present invention provides a novel apparatus for thermo-chemically removing a layer of surface metal from a ferrous metal body, preferably while the body is at an elevated temperature and moving along a roll table from one rolling operation to another and provides apparatus adaptable for eliminating scale from such a body. The conditioning or desurfacing units or heads are constructed and arranged so that bodies of different transverse dimensions can be readily conditioned without dismantling all or a portion of the apparatus. Thus, the present invention provides apparatus which can be readily used for conditioning or desurfacing different sizes of steel bodies such as are commonly produced by a steel mill.

Accordingly, the principal objects of this invention are to provide improved apparatus for surface conditioning all of the longitudinal surfaces of a metal body at a single pass; to provide such apparatus particularly adapted for removing a layer of surface metal from longitudinal surfaces of successive ferrous metal bodies of different transverse dimensions; to provide such apparatus in which the conditioning heads are constructed and arranged so as to be readily adjustable according to the cross-sectional dimensions of the particular body being condi-

tioned; to provide such apparatus which includes a raising and lowering mechanism for supporting and maintaining the conditioning heads in operative positions adjacent such a body; to provide a mechanism for supporting and maintaining the conditioning heads in an operative position adjacent the corresponding longitudinal surfaces and which includes means normally tending to urge such units toward the operative positions when displaced therefrom; to provide such apparatus which includes means for locking the conditioning heads in either the open and inoperative position or the closed and operative position; to provide such apparatus including a conditioning head for each longitudinal surface to be conditioned and means for adjusting the effective width of each head according to the exposed or operating width of the head and according to the transverse width of the corresponding longitudinal surface; and, to provide such an arrangement of blowpipe heads for conditioning at least two adjacent longitudinal surfaces of a ferrous metal body that at least one of the heads may be readily adjusted transversely relatively to one of the other heads to vary its exposed width according to the width of the corresponding longitudinal surface.

These and other objects and novel features of this invention will become more apparent from the following description taken in connection with the accompanying drawings, in which:

Fig. 1 is an isometric view of an exemplary slab desurfacing machine embodying the principles of the present invention and installed in a roll table such as is employed in a steel mill;

Fig. 2 is a front elevational view of the desurfacing machine of Fig. 1 with a portion broken away and with portions removed to more clearly disclose the construction;

Fig. 3 is a plan view of the machine of Fig. 1 with a portion broken away and with portions removed to more clearly show the construction;

Fig. 4 is a front elevational view on an enlarged scale of the right-hand desurfacing unit with the covers removed and schematically showing the relation of the heads of the left-hand unit;

Fig. 5 is a side view partially in section of the right-hand conditioning unit of Fig. 4 and with some parts removed more clearly to show the transversely slidable mounting means for this unit;

Fig. 6 is a fragmentary view of the heads arranged for desurfacing a slab having a smaller

vertical or thickness dimension than the slab of Fig. 4;

Fig. 7 is a fragmentary view of the heads arranged for desurfacing a slab of smaller transverse dimensions than the slab of Fig. 4;

Fig. 8 is a front elevational view of a desurfacing machine embodying the principles of the present invention and adapted for conditioning substantially square steel bodies in the diamond position;

Fig. 9 is an isometric view of an exemplary desurfacing machine embodying the principles of the present invention and more particularly adapted for conditioning substantially square steel bodies in the flat position;

Fig. 10 is a front elevational view of the machine of Fig. 9 with portions broken away to more clearly show the locking means;

Fig. 11 is an enlarged fragmentary view of the locking means in the closed or locked position;

Fig. 12 is a fragmentary schematic view of heads, similar to the heads of Fig. 10, arranged for desurfacing a billet of large cross-sectional dimensions; and,

Fig. 13 is a fragmentary schematic view of the heads of Fig. 12 arranged for desurfacing a billet of smaller cross-sectional dimensions to illustrate a slightly different method of adjusting the heads.

Referring to the drawings and more particularly to Figs. 1 to 7, a desurfacing machine A may be mounted on a fixed foundation for permanent installation in the roll table conveyor C such as is usually employed in steel mills for conveying metal bodies, but, the desurfacing machine A is preferably mounted on the motor-driven carriage W on the rails R for transverse movement into and out of alignment with the roll table C. The desurfacing machine is shown as being adapted for simultaneously desurfacing the four longitudinal surfaces of an elongated ferrous metal body such as a steel slab S, or the like. The slab S is supported on the rollers 20 of the roll table C. The rollers 20 are mounted on axles which are connected through suitable bevel gearing to one or more of the usual roll table motors, the gearing and the drive shaft and the drive motor not being shown in the interest of greater clarity in the drawings. Thus, when the roll table motor is energized, the slab S is moved along the roll table C past or through the desurfacing machine A. A freely rotatable, idler roller 19 (Fig. 3) may be mounted on the carriage W for additionally supporting the slab when being conditioned. The right and left desurfacing units E and F are substantially similar and are each similarly supported by suitable linkage for independent vertical floating movement and for transverse floating movement in unison so that the units can readily follow warped or bent slabs to simultaneously desurface all four longitudinal surfaces at a single pass.

Each unit E and F includes two adjacent angularly disposed blowpipe heads which are so constructed and arranged that slabs of different cross-sectional sizes or dimensions may be readily, successively desurfaced. The construction of the desurfacing units and the means for supporting them will later be described in detail.

The desurfacing units E and F are similar, the right-hand unit E being adapted and positioned for desurfacing the right-hand and bottom longitudinal surfaces of the slab S and the desurfacing unit F being adapted to desurface the left-hand

and top longitudinal surfaces of the slab S. The desurfacing unit E includes two heads 22 and 23 for desurfacing the corresponding longitudinal surfaces 25 and 26 of slab S, and the unit F includes two heads 28 and 29 for desurfacing the corresponding longitudinal surfaces 30 and 31 of the slab S. Heads 22 and 23 and heads 28 and 29 are similar and oppositely disposed. Actually, the heads 23 and 29 may each comprise one or more separate, similar sub-units but these sub-units are maintained in fixed alignment and in effect form single heads and, accordingly, the heads 23 and 29 will be referred to as single heads. Each of the heads includes at least one nozzle block 33 (Fig. 3) which is adapted to operatively receive a row of nozzles 34 and a nozzle protecting shoe 35 which entirely encloses the nozzles 34 except for the outlet ends thereof. Each nozzle 34 contains a central passage terminating in a relatively large discharge orifice for discharging a relatively voluminous stream of oxidizing gas such as oxygen, and contains one or more substantially parallel gas passages for a combustible gas mixture, such as a mixture of oxygen and acetylene, such combustible gas forming one or more high temperature preheating flames.

All of the nozzles of any one of the heads are so positioned and spaced as to apply a substantially sheet-like stream of oxygen of substantially uniform thickness at an acute angle against a relatively narrow transverse zone extending at least substantially across the corresponding longitudinal surface of the slab S, and to apply, if desirable, a row of high temperature preheating flames against such surface to heat a portion of the surface metal to the oxygen ignition temperature and/or to aid in maintaining the cut and more efficiently removing surface metal from the slab when the slab is moved relatively thereto.

Each nozzle block 33 is adapted to separately supply oxygen to the oxygen passage of each of the nozzles 34 therein and to separately supply a combustible gas mixture to the preheat passages of each of the nozzles. Both the nozzle block 33 and the nozzle shoe 35 of each head are preferably adapted to circulate cooling water therethrough to prevent overheating of the head and possible preignition of the gases. Each nozzle shoe 35 is preferably adapted to bear against and slide along the corresponding longitudinal surface to accurately position the nozzles relative thereto and, to prevent excessive abrasion or wearing away of the shoe, a layer of abrasion-resistant metal 36 may be deposited on the surface of each shoe that slidably engages the slab. The heads 22, 23, 28, and 29 may be any suitable type and may be the same as or similar to the blowpipe heads described in the copending United States application, Serial No. 334,510, filed May 11, 1940, by A. M. Keller, J. H. Bucknam, and A. J. Miller.

On the carriage W there are two similar right and left-hand columns 38 and on each of these columns at 39, there is pivotally mounted by means of suitable pillow blocks one end of a link 40. A plate or back link 41 is pivotally connected at each end to an outer end of one of the links 40. The two links 40 and plate 41 form a parallelogram linkage and plate 41 can float or move horizontally. A pair of upper and lower links 42 are each pivotally mounted at one end to the plate 41 as at 43 and, a similar pair of links 44 are pivotally connected as at 45 to the

plate 41. A plate 47 is pivotally connected to the outer ends of the links 42 and a similar plate 48 is connected to the outer ends of the links 44. The links 42 and plate 47 form a parallelogram linkage and plate 47 can float independently vertically and can float horizontally in unison with the plate 41 and similarly, the links 44 and plate 48 form a parallelogram linkage and plate 48 can float independently vertically and can float horizontally with back plate 41. Thus, the plates 47 and 48 can independently float or move vertically and can float or move horizontally in unison. The movement of plates 47 and 48 is confined substantially but not entirely within a vertical transverse plane relative to the longitudinal axis of the slab S. The previously described linkage for supporting the desurfacing units is similar to the linkage described in the United States Patent No. 2,210,921 to H. W. Jones, J. H. Bucknam, and E. A. Doyle.

On each of the similar plates 41 and 48 there is formed upper and lower ways 49 in which is horizontally slidingly mounted a plate 50. On each plate 50 there are formed or attached two outwardly extending supporting pins 51 and 52 on which is removably mounted either the right or left-hand carrier plate 53 or 54. On the right-hand carrier plate 53 there is mounted the right-hand desurfacing unit E and, the left-hand desurfacing unit F is mounted on the left carrier plate 54. An air or hydraulic cylinder 55 is resiliently attached to each of the plates 47 and 48 by means which is more fully described later and the piston rod 56 of each cylinder 55 is connected to the corresponding carrier plate 50. Thus, when air or fluid is admitted under pressure to the head ends of the cylinders 55, the units E and F are moved horizontally toward each other and toward the slab S and, when air or fluid is admitted under pressure to the rod ends of the cylinders 55, the units E and F are moved horizontally apart and away from the slab S.

Across the top of the columns 38 there is a box-like housing 58 which may be preferably cooled by means such as a water spray, not shown and in one end of which is pivotally mounted at 59 a lever 60. The inner end of the lever 60 is connected by means of a cable 61 to the floating plate 47 and the outer end of the lever 60 is pivotally connected to the upper end of the piston rod 62 of the hydraulic or air cylinder 63 pivotally mounted in the right-hand column 38. When air or fluid under pressure is admitted to the top or rod end of cylinders 63, the unit E is raised vertically toward the slab S and when the air or fluid pressure in the rod end of cylinder 63 is relieved the unit E is lowered by gravity. Also, in the housing 58, there is pivotally mounted at 66 a lever 69. The inner end of lever 69 is connected to the floating plate 48 by means of a cable 70 and, the outer end of lever 69 is connected to the upper end of a piston rod 71 of an air or hydraulic cylinder 72 pivotally mounted in the left-hand column 38. When fluid or air under pressure is admitted to the rod end of cylinder 72, the unit F is raised away from the slab S and when the pressure in the rod end is released the unit F is lowered toward the slab S by gravity.

By admitting fluid or air at a predetermined pressure into the rod end of cylinder 63 the pressure of the head 23 upwardly against the bottom longitudinal surface 26 can be accurately maintained. Similarly, by maintaining a predetermined lower pressure in the rod end of cylinder

72, the weight of the unit F can be partially counter-balanced so that the pressure of head 29 against the longitudinal surface 31 is the desired pressure. Additionally, the cylinders 55 may urge the heads 22 and 28 against the corresponding longitudinal surfaces 25 and 30 at a predetermined pressure. Thus, each of the four heads can be supported in operative position adjacent its corresponding longitudinal surfaces of slab S and can be urged toward such surface at a predetermined pressure.

The four heads 22, 23, 28, and 29 are so constructed and arranged that the heads may readily be positioned to successively desurface slabs of different cross-sectional dimensions or retained in position to successively desurface slabs of the same cross-sectional dimensions. The head 23 is fixedly attached by bolts or other suitable means to the carrier plate 53 and the head 22 is movably or adjustably attached to the carrier plate 53. As shown more particularly in Fig. 4, the head 22 is attached to a plate 74 and, three similar bolts 73 extend through the elongated vertical slots 75 formed in the plate 74 and threadedly engage the carrier plate 53 to movably attach the slide plate 74 to the carrier plate. A lead screw 76 is rotatably mounted in the carrier plate at 77 by means of the two collars 78 and the screw 76 threadedly engages the slide plate 74 at 79. Thus, when the screw 76 is turned the head 22 is moved vertically and parallel to and transversely of the surface 25. The head 29 is fixedly attached to the left-hand carrier plate 54 and head 28 is slidably attached to the carrier plate 54 for vertical movement by means of a lead screw similar to the way the head 22 is mounted on plate 53 and is vertically movable by means of screw 76.

When the heads are in operative positions adjacent the corresponding longitudinal surfaces of the slab S, a similar end 82 of each head is positioned substantially flush with the edge of the corresponding longitudinal surface and the end 82 is positioned inside of the adjacent head so that each head may be adjusted transversely of and parallel to its corresponding surface without interference between any of the heads. Each head is as wide as the widest surface to be desurfaced and the heads 22 and 28 are as wide as the vertical thickness of the largest slab to be desurfaced and the heads 23 and 29 are as wide as the horizontal width of the largest slab to be desurfaced. When such largest slab is being desurfaced the full width of each head is exposed as shown in Fig. 4, but, when a smaller slab is to be desurfaced, the exposed width of each head is less as more clearly shown in Figs. 6 and 7.

By means of the screws 76, the exposed widths of the heads 22 and 28 can be readily and similarly adjusted to be equal to the vertical thickness of the slab as shown in Figs. 6 and 7 and the distance between the heads 23 and 29 can be varied according to the exposed widths of the other two heads by means of the cylinders 63 and 72. The minimum distance between the heads 22 and 28 and the exposed width of each of the heads 23 and 29 can be adjusted by means of an adjustable stop. In each of the carrier plates 53 and 54 there is a threaded bolt 81, each adapted to contact a stop 84 formed on each of the corresponding plates 47 and 48 and the limit of horizontal movement of the units E and F toward each other and toward the slab S may be varied according to the horizontal transverse width of the slab by means of bolts 81. The cyl-

inders 55 resiliently urge the heads 22 and 28 toward the slab and after the bolts 81 have been correctly adjusted the exposed widths of the top and bottom heads 29 and 23 vary according to the horizontal width of the slab. When desurfacing a slab, the four heads always enclose an area of substantially the same dimensions as the cross-sectional area of the slab.

To successive'y desurface slabs of different cross-sectional dimensions, each head must be so positioned that a similar end of each head is inside of the head adjacent such end, and, each head must be adjustable in a direction parallel to and transversely of the corresponding longitudinal surface. Slabs other than four-sided, rectangular slabs may be desurfaced by increasing the number of heads. Additionally, the heads could be arranged in an anti-clockwise direction instead of a clockwise direction as shown.

Each unit E and F includes means for varying the effective width of each head or the width of each oxygen stream and the width of the row of preheating flames according to the exposed width of each head. Each unit is similar and only unit E will be described in detail. On the carrier plate 53 there is mounted a relatively large cutting or desurfacing oxygen header 86 which communicates with a suitable source of relatively high pressure oxygen. To the head 23 there are connected a plurality of lengths of tubing 87 equal in number to the nozzles in the head 23. Each length of tubing communicates through a valve 89 with the head 86 for separately supplying oxygen to the central passage of a corresponding nozzle 34. Also connected to the head 23 are a number of lengths of supply tubing 90 for separately supplying a combustible gas mixture to each of the nozzles, and each length of tubing 90 communicates with a gas mixer 91. The preheat oxygen header 92 communicates through a length of flexible hose with a suitable supply source and the header 92 separately communicates through a valve 93 and a length of tubing with each of the mixers 91. The acetylene header 95 also communicates through a suitable length of flexible hose with a source of acetylene supply and header 95 separately communicates through a valve 96 and a length of tubing 97 with each of the mixers 91. Thus, by means of the oxygen valves 89 and the preheat gas valves 93 and 96 any number of the nozzles may be individually blank-off, to vary the effective width of the head, i. e., effective width of the composite sheet-like oxygen stream and the width of the zone across which the preheat flames extend. The gas supply for each of the nozzles of the head 22 is similarly controlled, and the gas supply for each of the nozzles in the heads 28 and 29 is similarly controlled.

A length of tubing 125 communicates with a source of water supply and is connected to the head 23 for supplying cooling liquid, such as water, thereto. A length of tubing 126 communicates with heads 23 and 22 and after the water flows through head 23, it flows through head 22 and through the outlet tubing 127 to a drain, not shown. It is also desirable to prevent overheating of the gas supply tubes and three perforated pipes 128 communicate with a suitable water supply and are so positioned as to spray water over the gas supply tubes and the mixers of heads 22 and 23. The heads and gas supply tubes of unit F are similarly prevented from overheating.

The main gas and water supply hoses 129 of Fig. 1 communicate with control columns V and 75

V', each containing suitable valves and pressure regulators for controlling the gas and water supply and for maintaining the gases at the desired predetermined pressure.

5 When a slab is being desurfaced, each of the desurfacing units is normally urged toward the slab S by the corresponding cylinder 55 and each cylinder is similarly and resiliently mounted for limited movement to absorb shocks and prevent 10 damage to the desurfacing units. The right-hand cylinder 55 is pivotally connected at its rear end to an arm 99 which is pivotally connected at 100 to the plate 47. To the opposite end of the arm 99 there is connected a clevis attached to or formed on the end of a rod 101 which extends through a portion 102 formed on or a part of plate 47. On the threaded outer end of rod 102 there is a nut 103 and a washer 104. The compressed spring 106 is confined on the rod 101 between the washer 104 and the portion 102. The spring 106 is preloaded so as to normally urge the arm 99 and the cylinder 55, toward the left as far as the arm 99 is movable. Thus, pressure or shock applied against the head 22 by the slab S will move the desurfacing unit E toward the right against the action of spring 106. The left-hand cylinder 55 is similarly resiliently connected to the plate 48. Thus, both desurfacing units E and F have limited, resilient transverse movement.

As has been previously pointed out, the fluid or air pressure in the cylinders 63 and 72 is such that the heads 23 and 29 exert a pressure against the bottom and top surfaces of the slab S. Thus when desurfacing a slab on the flat as shown, the units E and F can be moved vertically toward each other, or moved vertically and horizontally toward each other, on'y when the slab is in position to limit the vertical movement of the units. Each head 23 and 29 has formed thereon or attached thereto an outwardly projecting finger 124 so that the units will be certain to engage the slab S when moved toward it.

This desurfacing machine may be readily adapted for desurfacing ferrous metal bodies in the diamond position by substituting Y-shaped carrier plates as shown more particularly in Fig. 8 and which will be described later in more detail. When desurfacing a body in the diamond position, it is necessary that the units be normally maintained at the desired level and accordingly, the previously described counterbalancing mechanism of Fig. 2 is provided with the steadyng or centering means which causes the desurfacing units to each normally float substantially at the desired level. This centering means is only essential when desurfacing a body in the diamond position and is so constructed and arranged that when desurfacing a body in the flat position, as shown in Fig. 2, the units E and F would be normally maintained at such a level that the heads 23 and 29 would contact or almost contact each other, if the slab S did not interfere.

Thus, in the following description of the centering means, the movement of the units E and F will be described when the units are adapted to desurface a body in the diamond position. In the housing 58, on the right-hand lever 60, there is formed an upwardly extending portion having a pin 108 therein engaging an elongated slot 109 formed in a clevis 110 attached to or formed on the end of a rod 111. The rod 111 extends through a collar 112 pivotally mounted in the housing 58. A spring 113 is confined on the rod

111, and normally urges rod 111 toward the right as shown in Fig. 2. When the desurfacing unit E is in the lowered position, the spring 113 is fully compressed and when air or fluid under pressure is admitted to the rod end of the lifting cylinder 63, the spring 113 aids in lifting the unit E toward the slab S. The spring 113 is so proportioned as to only aid in lifting the unit E until the heads are substantially at a normal operative level. The pressure in the head end of the cylinder 63 is not enough to lift the right-hand desurfacing unit without the aid of the spring 113. Thus, if desurfacing unit E is displaced upwardly, gravity tends to restore it to the normal level and if displaced downwardly, the spring 113 aids in raising it to its normal position. By means of the nut 114, the tension of spring 113 can readily be adjusted to vary the normal or floating level of the unit E.

On the lever 69 there is formed an upwardly extending portion having a pin 116 therein engaging an elongated slot in the clevis 117 formed on or attached to one end of the rod 118. The rod 118 extends through a member 119 and has a nut 120 threaded on its outer end for confining a spring 121 on the rod, between the nut 120 and member 119. The spring 121 normally urges the rod 118 toward the right. When the desurfacing unit F is in the raised position, the spring 121 is compressed and when the pressure in the rod end of cylinder 72 is lowered to a predetermined pressure, the desurfacing unit F is lowered toward the slab S by gravity and the force of spring 121 until counterbalanced by the cylinder 72. By selecting the correct pressure for the rod end of cylinder 72 and by correctly varying the tension of spring 121 by means of nut 120 the desurfacing unit F can be maintained at the desired level during the desurfacing operation. If the unit F is displaced upwardly by the slab, the spring 121 is compressed to urge the desurfacing unit downwardly toward its normal position. If the desurfacing unit F is displaced downwardly below the desired level, the spring 121 exerts no force and the cylinder 72 will urge the desurfacing unit upwardly toward its normal position. If the springs 113 and 121 or some other suitable similar acting means was not employed, the counter-balanced desurfacing units E and F would not return to their normal positions when displaced therefrom.

This centering means is so constructed and arranged as not to interfere when desurfacing a body on the flat. The force exerted by the springs 113 and 121 affects the pressure of the heads 23 and 29 against the slab S and this force must be taken into consideration when determining the pressures to be maintained in the counterbalancing cylinders. Accordingly, this machine may be readily adapted for desurfacing a body in either the flat or diamond position by merely changing the carrier plates and heads.

When the units E and F are in the operative positions adjacent the slab as shown in Fig. 1, the heads are substantially coplanar, i. e. the fronts of all the heads are substantially in the same transverse plane, and each of the coplanar heads 22, 23, 28, and 29 is maintained adjacent the corresponding longitudinal surface irrespective of the cross-sectional dimensions of the slab. When a rectangular body of a different cross-sectional size is to be desurfaced, the operator by turning the lead screws 76 can readily separately adjust the heads 22 and 28 vertically to vary the

exposed widths of these heads according to the widths of the corresponding surfaces 25 and 30, respectively. The cylinders 55 resiliently urge each unit E and F toward the slab so that the distance between the heads 22 and 28 and the exposed width of each head 23 and 29 is varied according to the width of the corresponding bottom longitudinal surface 26 and top longitudinal surface 31, respectively. It will be seen that the 10 shoes of the blowpipe heads in their operative positions always cooperate to form the four sides of the border of a rectangular passage through which the elongated metal body is propelled. With this construction and arrangement of the heads, different sizes of bodies can readily, successively be desurfaced without laboriously mounting different heads and shutting down and dismantling the machine.

The desurfacing machine of Figs. 1 to 7, inclusive, may be operated by any suitable means but is preferably operated through a remote control system such as or similar to the control system shown in the United States Patent No. 2,244,822 to J. H. Bucknam. In general, this machine is operated in the usual manner. The slab S is moved along the roll table until the starting end is in position, the roll table is then stopped and the units E and F are moved toward the slab and the preheating flames are turned on to heat a starting zone to the ignition temperature. If the slab is at a high enough temperature, it is not necessary to employ such preheating flames, or, other means such as an electric arc may be used for preheating an initial portion, but generally it is desirable to use such preheating flames for starting the cut and for aiding in maintaining the desurfacing reaction. After a portion of the slab has been heated to the ignition temperature, cutting oxygen is turned on and simultaneously the roll table motor is energized to cause the slab to move along the roll table past the desurfacing heads to progressively desurface all four longitudinal surfaces of the slab.

When a slab having different cross-sectional dimensions is to be desurfaced, the operator must adjust the heads as previously described and by means of the adjusting screws 76, adjusts each of the heads 22 and 28 vertically until the exposed widths of each head is equal to the vertical thickness of the slab and then by means of the corresponding valves 89, 93, and 96, the gas supply for part of the nozzles of these side heads is either turned completely off or on to vary the width of the composite preheating and desurfacing oxygen streams according to the exposed width of these heads. By means of the adjusting screws 81, the operator can quickly adjust the minimum distance between the heads 28 and 22 when in the closed position and the exposed width of heads 28 and 22 according to the horizontal width of the slab. Also by means of the gas-controlling valves, the effective widths of the heads 29 and 23 are correspondingly adjusted according to the exposed widths of these heads. Such adjustment of the heads only takes a relatively short time and after adjustment, the four heads when in the closed operative position enclose an area of substantially the same dimensions as the cross section of the slab to be desurfaced and each longitudinal surface of the slab is conditioned at a single pass.

The embodiment of the invention shown in Fig. 8, is similar to the machine shown in Figs. 1 to 7, and is adapted for desurfacing substantially

square bodies such as steel bars, billets, and the like when such bodies are in the so-called diamond position, with all longitudinal surfaces at a transverse angle of 45° relative to either a horizontal or vertical plane. Portions of apparatus have been broken away and the gas supplying pipes and tubing and other minor portions of the apparatus have been removed to more clearly disclose the structure.

The desurfacing units E' and F' are similar to the units E and F and are similarly mounted. As the supporting linkage for the units E' and F' is the same as for units E and F such supporting linkage will not be again described. The heads 131, 132, 133, and 134 are similar to and are mounted substantially the same as the heads 22, 23, 28, and 29 respectively. The heads 132 and 134 are fixedly mounted on the respective Y-shaped carrier plates 135 and 136 of units E' and F' and the heads 131 and 133 are slidably mounted on the respective carrier plates 135 and 136. Each head 131 and 133 may be adjusted transversely of and parallel to the correspondingly longitudinal surface of the bar B by means of the respective adjusting screws 137 and 137' similar to the way heads 22 and 23 can be adjusted. The heads of Fig. 8 are each inclined at an angle of 45°, relatively to either a horizontal or vertical. When the units E' and F' are in the operative positions adjacent the bar B, each of the heads is maintained adjacent a corresponding longitudinal surface irrespective of the cross-sectional dimensions of the steel body and the heads enclose an area of substantially the same dimensions as the dimensions of the cross-sectional area of the bar B. The heads are so constructed and arranged that the machine may be quickly adapted for desurfacing bodies of different cross-sectional dimension. While these heads are shown as being arranged for desurfacing a square body such as a bar B, they can be relatively easily adjusted for desurfacing bodies in the diamond position which are not square. The means for moving the units E' and F' toward and away from the body is similar to the means employed for moving the units E and F toward and away from the slab S, while the steadyng means for maintaining the units E' and F' normally at the desired level, is slightly different from the means for steadyng the units E and F.

Referring more particularly to Fig. 8, the outer end of lever 138 is connected to an upper end of a piston rod of a pivotally mounted, counterbalancing cylinder in the right-hand column of the machine. The inner end of the lever 138 is connected by means of a cable to the right-hand desurfacing unit E' and when air or liquid under pressure is admitted to the rod end of the counterbalancing cylinder, the unit is raised and when this pressure is lowered or released, the unit is lowered by gravity. The upwardly extending portion of lever 138 contains a pin 139 engaging a slot in the clevis 140 formed on or attached to the rod 141 which extends through the pivotally mounted collar 142. On the outer end of the rod 141 there is threaded a nut or an adjustable collar 143 and, a spring 144 is confined on the rod 141 by means of the nut 143 and the collar 142. With the unit E' in the lowered position, air or fluid may be admitted to the rod end of the counterbalancing cylinder at a predetermined pressure to raise the unit E'. If the unit E' is displaced upwardly from the operative position, gravity and spring 144 tend to lower the unit to

the normal level and if the unit is displaced downwardly, the counterbalancing cylinder urges the unit upwardly to its normal level.

The left-hand lever 146 is connected to the desurfacing unit F' and to a counterbalancing cylinder similar to the lever 69 of Fig. 2. In the upper portion of the lever 146 there is a pin 148 engaging the elongated slot of the clevis 149 formed on or attached to the rod 150 which extends through the pivotally mounted collar 151. A spring 152 is confined on the rod 150 between the collar 151 and the adjustable collar or nut 153. Thus, if the unit F' is displaced upwardly from the normal position, gravity urges the unit downward towards its normal position. If the unit F' is displaced downwardly, the spring 152 and the counterbalancing cylinder urge the unit upwardly to its normal position. By adjusting the nuts or collars 143 and 153, and/or the pressure in the cylinders, the operator can readily adjust the normal operative level of the units E' and F', respectively.

The machine shown in Fig. 8 can readily be adapted for desurfacing a body in the flat position by changing the carrier plates and heads. It has been found in practice that the centering means is not entirely satisfactory when desurfacing on the flat as the springs 144 and 152 so tend to decrease the pressure exerted by the bottom and top heads against the body that the desurfacing units do not always follow the body when it is slightly irregular. Accordingly, when desurfacing on the flat the centering means is preferably disconnected by removing pins 139 and 148. It has been found in practice that the centering means of Fig. 8 is preferable, as compared to the centering means of Fig. 2, when desurfacing on the diamond.

The desurfacing machine shown in Fig. 8 can be readily adjusted for successively desurfacing bodies of different cross-sectional dimensions and the means for adjusting the heads is substantially the same as the means for adjusting the heads of the machine shown in Fig. 1. As shown in Fig. 8 the heads are positioned for desurfacing a bar B of a smaller cross section than the heads can be adapted for desurfacing. The heads 131 and 133 can be moved transversely of and parallel to the corresponding longitudinal surfaces by means of the lead screws 138 and 139 to vary the exposed width of each of the heads 131 and 133 according to the transverse width of the corresponding longitudinal surface. The heads 132 and 134 can be adjusted transversely of and parallel to the corresponding longitudinal surfaces by adjusting the units E' and F' horizontally to vary the exposed width of each of the heads 132 and 134 according to the width of the corresponding longitudinal surfaces. A similar end of each of the heads is always inside of the work-contacting surface of the head adjacent thereto and each head includes valve means for varying the effective width of the head according to the exposed width of the head and according to the width of the corresponding longitudinal surface.

The method of operating the machine of Fig. 8 is substantially the same as the method of operating the machine of Fig. 1, except that, when desurfacing on the diamond, the units need not be moved vertically and only need to be moved horizontally toward or away from the body. When the apparatus of Fig. 8 is used for desurfacing a body on the flat, the desurfacing units

are moved both horizontally and vertically toward and away from the body. Accordingly, the method of operating the machine of Fig. 8 need not be described in detail.

Figs. 9 to 11 illustrate a desurfacing machine similar to the machine of Fig. 1 but more particularly adapted for conditioning steel bodies such as billets, and the like. The link mechanism for supporting the right and left-hand desurfacing units **X** and **Y** is similar to the linkage for supporting the desurfacing units **E** and **F** of the machine of Fig. 1 and accordingly this mechanism is not again described in detail. Each of the units **X** and **Y** may be individually raised and lowered by air or hydraulic cylinders mounted in the respective side columns similar to the way that the units **E** and **F** are raised and lowered. The mechanism for supporting and for raising and lowering the units **X** and **Y** is very similar to the mechanism described in the previously mentioned copending application, Serial No. 145,480. The machine of Figs. 9 to 11 does not employ centering means but does include means for locking the desurfacing units in either the open position or the closed position.

The right-hand desurfacing unit includes a fixedly mounted desurfacing head **156** and a slidably mounted head **157** which may be moved vertically by means of the lead screw **158** in a manner similar to the way head **22** is moved vertically by the screw **76**. The left-hand desurfacing unit includes a fixedly mounted head **159** and a slidably mounted head **160** which may be moved vertically by means of the screw **161**. The heads **157**, **156**, **159**, and **160** are similar to and are mounted in the same manner as the heads **22**, **23**, **29**, and **28** to successively desurface steel bodies such as billets having different cross-sectional dimensions or having the same cross-sectional dimensions.

Attached to a lower portion of the mechanism for supporting unit **X** is a transverse plate **163** having a portion **164** attached to or formed on the other end thereof. A member **165** is fastened to the portion **164** by means of bolts or other suitable means. Attached to the lower end of the unit **Y** is a plate **166** having pivotally attached thereto an air or hydraulic cylinder **167**. A bell crank **168** is pivotally mounted at **169** on the plate **166** and has one arm connected to the outer end of the piston rod **167'** of cylinder **167**. A roller **170** is mounted in the end of the other arm of the bell crank for engaging a cam surface **171** formed on the member **165**. A bolt **172** threadedly engages and extends through member **165**. An outwardly projecting stop **173** is also formed on or attached to the plate **166**. A rectangular vertical slot **175** is formed in the portion **164** and a correspondingly shaped tongue **176** is formed on the plate **166** for engaging the slot **175**.

When the desurfacing units are in the open or inoperative position as shown in Fig. 10 the roller **170** engages the cam surface **171** as shown. When the desurfacing units **X** and **Y** are moved upwardly and downwardly, respectively, toward the billet to the closed or operative position, tongue **176** enters into the slot **175** and the vertical movement of the desurfacing units may continue until the inner end of bolt **172** strikes the stop **173**. Thus, by adjusting the bolt **172**, the distance between the heads **156** and **159** may be readily adjusted. By admitting air or fluid under pressure to the rod end of the cylinder **167** the bell crank **168** is urged in an anti-clockwise direction at which time the roller **170** engages the lower sur-

face **177** of the portion **165** and as long as the pressure is maintained in the rod end of the cylinder **167** the two desurfacing units are locked together and will move vertically and horizontally in unison. Each of the desurfacing units **X** and **Y** is horizontally slidably mounted similar to the units **E** and **F** and, thus, units **X** and **Y** may be moved horizontally toward and away from each other and the billet **D**.

Preferably, this machine is operated by means of one or more suitable controls located at a remote control point out of the zone of high temperature heat. When a billet having a different vertical thickness than the previously desurfaced billet is to be desurfaced, the operator must first adjust the stop **172** to vary the distance between the top and bottom heads and must vertically adjust the heads **157** and **160** by means of screws **158** and **161** to vary the exposed widths of these heads according to the widths of the corresponding longitudinal surfaces. Also the effective width of each of the heads must be correctly adjusted. After these adjustments have been made, the roll table motor is momentarily energized to move the billet to the starting position so that the starting end of the billet extends at least a short distance rearwardly of or beyond the heads.

When the billet is in position, air or fluid under pressure is admitted to the pneumatic counterbalancing means for unit **X** and simultaneously the air or fluid pressure in the pneumatic counterbalancing means for unit **Y** is at least partially released so that unit **X** is raised and unit **Y** is lowered towards each other and the billet. As the units move toward each other the tongue **176** engages the groove **175**. This movement is limited by both the stop **172** and the billet or by the billet alone. A finger **188** is formed on each of the heads **156** and **159** and these fingers strike the billet even when the units are horizontally wide apart. The fingers **188** by engaging the billet cause the units **X** and **Y** to be maintained at the proper level. After the units have been moved vertically towards the billet, air or fluid is admitted to the rod end of the locking cylinder **167** to lock the units together and air or fluid is also admitted to the pneumatic means for moving the units horizontally towards the billet. As a similar end of each of the heads **157** and **163** is inside of the head adjacent thereto, the units continue to move horizontally until the heads **156** and **160** are adjacent the corresponding longitudinal surfaces and the exposed width of the heads **156** and **159** is varied according to the horizontal width of the billet.

The preheating flames preferably are turned on before the heads actually contact the billet to heat a zone of surface metal all around the billet to the ignition temperature; the oxygen is then turned on and simultaneously the roll table motor is energized to propel the billet longitudinally through and past the heads to thermo-chemically remove a layer of metal from the longitudinal surfaces.

After the billet has been desurfaced the oxygen may be turned off by either automatically or manually operable means and the units are unlocked and moved apart to the open position as shown in Fig. 10 by either automatically or manually operable means. The preheating flames may be turned off by either automatically or manually operable means and preferably after the heads are partially retracted. If the next billet to be desurfaced is a different size the heads **157**

and 160 and the bolt 172 must be adjusted before desurfacing this next billet.

In each of the machines of Figs. 1, 8, and 9, the desurfacing units are separately mounted on horizontal, vertically-swingable links so that each unit moves vertically through a slightly arcuate path. As the bottom surface of the body is supported on the roll table rollers the level of the bottom surface is substantially constant regardless of the vertical thickness of the billet. Therefore, when the vertical thickness of successive bodies varies over a wide range, one of the units may move an undesirable distance fore or aft relative to the other unit and it is necessary to provide some compensating means to maintain all of the heads substantially coplanar, such as, mounting the top head so that it may be adjusted vertically for a short distance. This may be accomplished by providing a plurality of threaded holes in the carrier plate so that the top head can be bolted to the carrier plate at the different desired levels.

Referring more particularly to Figs. 12 and 13, there is schematically shown a slightly different method of adjusting the heads. The right-hand unit 180 is similar to and is supported in the same manner as the unit E of Fig. 1, that is, the bottom head 181 is fixedly attached to the carrier plate and the right-hand head 182 is adjustably attached to the carrier plate for vertical movement. The left-hand desurfacing unit 184 is supported in the same manner as the unit F of Fig. 1, but, the top head 185 is adjustably attached to the carrier plate for vertical movement and the left-hand head 186 is fixedly attached to the carrier plate and is not movable vertically. The head 185 may be moved vertically by any suitable means, such as, a manually operable lead screw similar to the means for moving head 28 of Fig. 1. Fig. 12 shows the heads arranged for desurfacing a large billet of maximum cross-sectional dimensions and Fig. 13 shows the heads arranged for desurfacing a billet having smaller than maximum cross-sectional dimensions. In Fig. 13 the right-hand head 182 has been adjusted downwardly from its position as shown in Fig. 12 to shorten the exposed width of head 182 according to the vertical thickness of the billet. The top head 185 has also been adjusted downwardly which, in effect, varies the exposed width of the left-hand head 186 according to the vertical thickness of the billet. The units 180 and 184 also have been adjusted horizontally toward each other to vary the exposed widths of the top and bottom heads 185 and 181, respectively. Fig. 12 is similar to Fig. 4 in that the full width of each head is exposed and Fig. 13 is similar to Fig. 7 in that the exposed width of each head has been varied according to the width of the corresponding longitudinal surface. In both Figs. 4 and 13 the heads, in effect, have been moved toward a common center according to the cross-sectional dimensions of the body to be desurfaced.

By vertically adjusting the top head as shown in Figs. 12 and 13 the normal operating level of the left-hand desurfacing unit 184 remains substantially constant regardless of the vertical thickness of the billet and the normal operating level of the right-hand unit 180 remains substantially constant as the billet is supported on the roll table. Accordingly, with this arrangement of heads an indefinite range of sizes may be desurfaced without causing either of the units to move vertically and the heads remain substan-

tially coplanar at all times. If desirable the right-hand unit could be constructed similar to the left-hand unit, i. e., the bottom head 181 could be adjustably attached to the carrier plate for vertical movement and the right-hand head 182 could be either adjustably or fixedly attached to the carrier plate, though vertical adjustment of the bottom head 181 would cause the level of the unit 180 to change.

In each of the machines of Figs. 1, 8, 9, and 12 the desurfacing heads are each in effect relatively adjustable transversely of and parallel to the corresponding longitudinal surface of the work body to vary the exposed width of each head according to the width of the corresponding surface and to maintain a similar end of each head substantially flush with an adjacent surface edge and inside of the head adjacent thereto so that the heads may in effect each be moved toward and away from a common center to vary the dimensions of the enclosed area according to the cross-sectional dimensions of the work body. Thus the heads are so adjustably supported and arranged that successive bodies of different cross-sectional dimensions or of the same cross-sectional dimensions can be equally as readily desurfaced.

Having described the invention in detail, it is obvious that alterations could be made in the apparatus by one skilled in the art, without departing from the spirit or scope of this invention. For instance, the heads instead of being mounted in pairs as shown and described could be separately, adjustably mounted for independent universal movement in a common transverse plane. Also, blowpipe heads could be adapted for applying heating flames only for conditioning the longitudinal surfaces by thermally removing scale therefrom.

What is claimed is:

1. Apparatus for conditioning the longitudinal surfaces of an elongated ferrous metal body comprising in combination a plurality of blowpipe heads equal in number to the longitudinal surfaces to be simultaneously conditioned, each head being adapted to apply a gaseous stream against a corresponding longitudinal surface; means for supporting and longitudinally propelling such a body; means for supporting said heads adjacent said body when so propelled; means for adjusting each of said heads transversely of and parallel to the corresponding longitudinal surface to maintain a similar end of each head substantially flush with an adjacent surface edge and to vary the exposed width of each head according to the width of the corresponding longitudinal surface; means for adjusting said heads toward and away from the center of said body according to the cross-sectional dimensions of said body; and means for varying the effective width of each head according to the width of the corresponding longitudinal surface.

2. Apparatus for conditioning all of the longitudinal surfaces of successive ferrous metal bodies of different cross-sectional dimensions comprising in combination a plurality of substantially coplanar blowpipe heads each being equal in width to the widest corresponding longitudinal surface to be conditioned and each being adapted to apply a gaseous stream against a corresponding longitudinal surface; means for supporting said heads adjacent said surfaces; means for adjusting each of said heads transversely of the corresponding longitudinal surface to vary the exposed width of said head according to the

width of said surface and toward and away from the center of such a body according to the cross-sectional dimensions of said body; and means for effecting relative movement between said heads and said body longitudinally thereof.

3. Apparatus for successively conditioning elongated ferrous metal bodies having different cross-sectional dimensions or having the same cross-sectional dimensions and comprising the combination of means for successively supporting and longitudinally propelling such bodies; a plurality of substantially coplanar conditioning heads disposed adjacent corresponding longitudinal surfaces of such a body when so propelled, said heads being equal in number to the longitudinal surfaces to be conditioned simultaneously, and each of said heads having a maximum effective width substantially equal to the widest surface to be conditioned; mechanism for supporting and adjusting said heads transversely with respect to said body to vary the exposed width of each head according to the width of the corresponding surface of said body; and means for varying the effective width of each head according to the exposed width and according to the width of said corresponding longitudinal surface.

4. Apparatus for desurfacing two or more adjacent longitudinal surfaces of a ferrous metal body at a single pass comprising the combination of a plurality of desurfacing heads equal in number to said surfaces, said heads being each adapted to apply a substantially sheet-like stream of oxidizing gas against a relatively narrow transverse zone extending substantially across the corresponding longitudinal surface for thermo-chemical reaction with the surface metal; means for supporting said heads in desurfacing positions, said supporting means including adjusting devices arranged for adjusting each of said heads transversely of its corresponding surface of the body to position a similar end of each head inside of the head next adjacent thereto and for adjusting said heads toward and away from the center of said body according to the distance of the corresponding surfaces from said center, said heads being so adjustably supported as to desurface ferrous metal bodies of successively different cross-sectional dimensions; and means for relatively moving said heads and said body longitudinally thereof to progressively thermo-chemically remove a relatively shallow layer of metal from said surfaces.

5. In apparatus for successively desurfacing elongated metal bodies of different cross-sectional dimensions or of the same cross-sectional dimensions, a plurality of substantially coplanar heads equal in number to the longitudinal surfaces of such a body, each head being substantially equal in width to the widest corresponding surface to be desurfaced and each head being adapted to apply a substantially sheet-like oxygen stream against said corresponding surface, said heads when in the operating position enclosing an area substantially equal to the cross-sectional area of said body; means for supporting said heads in an operative position adjacent said body, said supporting means including mechanism for adjusting each head universally in a transverse plane relatively to the longitudinal axis of said body to vary the area enclosed by said heads according to the cross-sectional area of said body.

6. In a machine for successively conditioning elongated metal bodies, a plurality of surface

conditioning heads equal in number to the longitudinal surfaces of such a body and separately adapted to apply relatively wide gas streams against corresponding longitudinal surfaces of said body; means for supporting said heads in operative positions adjacent said corresponding surfaces; and means for separately adjusting each head and constructed and arranged to vary the exposed width of each head according to the width of the corresponding longitudinal surface and to maintain a similar end of each head positioned substantially flush with the adjacent longitudinal edge of the corresponding longitudinal surface.

7. In a desurfacing machine, a plurality of substantially coplanar desurfacing heads equal in number to the longitudinal surfaces of the ferrous metal body to be desurfaced, each such head being equal in width to the widest longitudinal surface of any such body to be desurfaced and adapted to apply an oxidizing gas stream against a transverse zone extending across such corresponding longitudinal surface; means for supporting said heads in operative positions adjacent said corresponding longitudinal surfaces; means for adjusting the width of the gas stream of each head according to the width of the corresponding surface; means for adjusting each of said heads transversely and parallel to the corresponding longitudinal surface of the body to vary the exposed width of each head according to the width of such corresponding longitudinal surface.

8. Surface conditioning apparatus comprising means for supporting and longitudinally moving a ferrous metal body; a pair of conditioning heads for conditioning two adjacent, longitudinal surfaces of said body, each of said heads being adapted to apply a gaseous stream of variable width against a corresponding longitudinal surface of said body; means for supporting said heads in an operative position adjacent said longitudinal surfaces for maintaining a similar end of each head substantially flush with a longitudinal edge of the corresponding surface, said heads being constructed and arranged to condition adjacent longitudinal surfaces of successive ferrous metal bodies having different or similar longitudinal surface widths.

9. In surface conditioning apparatus, two conditioning heads adapted for simultaneously conditioning adjacent corresponding longitudinal surfaces of a ferrous metal body; means for supporting said heads in an operative position adjacent said surfaces, said supporting means including mechanism for adjusting one of said heads transversely of and parallel to its corresponding surface of the body to vary the exposed width of said last-mentioned head according to the width of such corresponding surface, and means for moving both of said heads transversely of said body to move the second of said heads transversely of and parallel to its corresponding longitudinal surface of the body to vary the exposed width of said second head according to the width of said last-mentioned surface.

10. In a surface conditioning machine, a surface conditioning unit including a pair of adjacent, angularly disposed heads, each head being adapted to apply a gaseous stream against a longitudinal surface of an elongated ferrous metal body; means for supporting said unit in an operative position adjacent said longitudinal surfaces; means for effecting movement of one of said heads transversely relatively to the other

of said heads for varying the exposed width of said movable head according to the width of the corresponding longitudinal surface; and means for effecting relative movement between said unit and said body longitudinally thereof.

11. In a surface conditioning machine, a surface conditioning unit including a pair of adjacent, angularly disposed heads, each head being adapted to apply a gaseous stream against the corresponding longitudinal surface of an elongated ferrous metal body; means for supporting said unit in an operative position adjacent said longitudinal surfaces; means for effecting adjustment of at least one of said heads transversely relatively to the other of said heads for varying the exposed width of one of said heads according to the width of the corresponding longitudinal surface; and means for effecting movement of said unit transversely relatively to the longitudinal axis of said body for varying the exposed width of the other one of said heads according to the width of the other corresponding longitudinal surface, said heads being constructed and arranged so that the exposed width of each head can be varied according to the width of the corresponding longitudinal surface; and means for effecting relative movement between said unit and said body longitudinally thereof.

12. In a surface conditioning machine, a pair of angularly disposed surface conditioning heads adapted for conditioning two, adjacent corresponding longitudinal surfaces of a ferrous metal body; supporting and adjusting means for supporting said heads in operative position adjacent said longitudinal surfaces and for maintaining a similar end of each of said heads substantially flush with a similar edge of each of said surfaces, said heads and said supporting and adjusting means being constructed and arranged to vary the exposed width of each of said heads according to the width of the corresponding longitudinal surface; and means for varying the effective operating width of each of said heads according to the exposed width of each of said heads.

13. Apparatus for conditioning an elongated metal body such as a steel billet and the like comprising the combination of means for supporting and longitudinally propelling said billet; two surface-conditioning units, each comprising a pair of adjacent angularly disposed blowpipe heads and each head being adapted to project a wide gas stream against a corresponding longitudinal surface of said billet; two carrier plates each of which carries one of said units, said units including mechanism whereby one head of each unit is movable transversely relatively to the other head of the same unit to vary the exposed width of said movable head according to the width of the corresponding longitudinal surface; and mechanism for supporting and adjusting said carrier plates and said units transversely with respect to said body whereby said units are maintained in an operative position adjacent said body.

14. Apparatus as claimed in claim 13, in which said blowpipe units are so constructed and arranged that said blowpipe units may be adjusted transversely of said billet to adjust the distance between opposite heads of each unit according to the thickness of said billet therebetween.

15. Apparatus as claimed in claim 13 in which the outer end of said movable head of each unit is inside of the inner face of the said other head of the opposite unit so that said units may be adjusted transversely of said billet to adjust the

distance between the opposite movable heads of said units according to the thickness of said billet therebetween.

16. A machine for simultaneously conditioning the longitudinal surfaces of an elongated rectangular ferrous metal body comprising two pairs of blowpipe heads, each head being adapted to apply a substantially sheet-like oxidizing gas stream against the corresponding longitudinal surface of said body; two plates for separately supporting each of said pairs of heads, one head of each of said pairs being fixedly attached to a corresponding one of said plates and the other head of each of said pairs being adjustably attached to said corresponding plate for movement parallel to and transversely of the corresponding longitudinal surface; means for supporting said plates and the heads thereon in operative positions adjacent said body, said heads together substantially enclosing an area of the same dimensions as the cross-sectional area of said body and so arranged that said fixed heads are oppositely disposed and said adjustable heads are oppositely disposed, said supporting means including means for adjusting the distance between said fixed heads according to the thickness of the body therebetween; and means for adjusting the distance between said adjustable heads according to the thickness of said body therebetween, whereby said heads are arranged and supported for varying the dimensions of the area enclosed according to the cross-sectional dimensions of said body.

17. Apparatus for thermally surface conditioning an elongated ferrous metal body which comprises two sets of conditioning heads; means connecting together the heads of each of said sets; means for separately moving each of said sets toward and away from said body; separate pneumatic means for counter-balancing each of said sets and associated mechanism; and separate spring means associated with each of said pneumatic means, one of said spring means acting to progressively decrease the effect of gravity when the corresponding set is displaced below a predetermined level for returning said set to said level, and the other of said spring means progressively increasing the effect of gravity when the corresponding set moves above a predetermined level for returning the set to said last-mentioned level.

18. In apparatus for thermally conditioning longitudinal surfaces of a ferrous metal body, a pair of blowpipe heads; means connecting together said heads as a unit and maintaining said unit positioned for applying streams of gas against two adjacent longitudinal surfaces of said body; pneumatic means for partially counter-balancing said unit; a centering spring associated with said pneumatic means, said spring being so connected to said unit that when said unit is displaced below a predetermined level said spring aids in raising said unit to said level and when said unit is displaced above said level said spring has no effect and gravity urges said unit toward said level.

19. In apparatus for thermally conditioning longitudinal surfaces of a ferrous metal body, a pair of blowpipe heads; means connecting together said heads as a unit and maintaining said unit positioned for applying streams of gas against two adjacent longitudinal surfaces of said body; pneumatic means for over counter-balancing said unit; a centering spring associated with said pneumatic means, said spring

being so connected to said unit that when said unit is displaced above a predetermined level said spring aids the force of gravity in lowering said unit to said level and when said unit is displaced below said level said spring has no effect and said pneumatic means urges said unit upward toward said level.

20. In apparatus for conditioning a ferrous metal body, the combination comprising two pairs of blowpipe heads; a member separately supporting each pair of heads, each of said pairs being movable horizontally along the corresponding one of said members; and means for separately moving each of said pairs horizontally along said corresponding member and for resiliently urging said pairs toward said body, each of said moving means including an arm pivotally mounted on said member and resiliently movable a limited distance away from said body, and power-actuated means connected to said arm and one of said pair of heads, said arm providing means whereby the corresponding pair of heads may move a limited distance away from the normal position of said body against the action of said power-actuated means.

21. Apparatus for conditioning longitudinal surfaces of a ferrous metal body comprising in combination means for supporting and propelling such a body; a pair of conditioning units each including at least one blowpipe head; means for movably supporting each of said units adjacent said body and including mechanism for moving each of said units toward and away from said body; locking means adapted to connect said units together for movement in unison when said units are moved to operating positions adjacent said body; and means for actuating said locking means to lock said heads together in the operating position and to unlock said heads when moved to the non-operating position.

22. Apparatus for conditioning an elongated, rectangular, ferrous metal body comprising means for supporting and longitudinally propelling such a body; two blowpipe units, each adapted to condition two adjacent longitudinal surfaces of said body; a member for supporting each of said units; means for separately moving each of said units horizontally along one of said members toward and away from said body; means for moving said units and members vertically toward and away from said body; and locking means adapted to connect said members for vertical movement in unison when said members are moved vertically toward said body and each other a predetermined distance.

23. Apparatus for conditioning an elongated, rectangular, ferrous metal body in the flat position, comprising in combination two pairs of blowpipe heads; a carrier plate connecting together one of said pair of heads and maintaining the heads thereon positioned for applying gas streams against and along the bottom and one longitudinal side of said body; a second carrier plate connecting together the other of said pair of heads and maintaining the heads thereon positioned for conditioning the top and the other longitudinal side of said body; two members each supporting one of said carrier plates for horizontal movement toward and away from said body; means for separately vertically moving each of said members and its associated mechanism toward and away from said body; a vertically grooved member associated with one of said supporting members; a tongued member associated with the other of said supporting members, said

grooved and tongued members being adapted to engage each other when said supporting members are moved vertically towards said body and the closed position and to disengage when said supporting members are farthest away from said body in the open position; and releasable locking means adapted for locking said tongue and grooved members together so that said supporting members move vertically in unison only when in the closed position.

24. Apparatus for simultaneously thermo-chemically conditioning all four longitudinal surfaces of each of a succession of elongated metal bodies, all of such bodies being of rectangular cross-section but some of such bodies having cross-sectional sizes which differ within wide limits from the cross-sectional sizes of others of such bodies, such apparatus comprising, in combination, a group of four blowpipe nozzle means having shoes respectively forming the four sides of the border of a rectangular passage, said nozzle means being constructed and arranged to simultaneously discharge wide streams of surface conditioning medium against such four surfaces along a zone on and extending entirely around the rectangular periphery of a metal body propelled through said rectangular passage and engaged by said shoes, at least one of said nozzle means including the shoe thereof, constituting one of said four sides, being adjustable relatively to the other nozzle means and shoes of said group to change the cross-sectional size of said rectangular passage within such limits; and adjusting means for changing the position of at least one of said nozzle means and the shoe thereof, relatively to the other nozzle means and shoes of said group to form any selected one of a plurality of rectangular passages of different cross-sectional sizes within said limits and thereby arrange said group of nozzle means to simultaneously discharge wide streams of such medium against the four longitudinal surfaces of any selected one of a plurality of metal bodies of different cross-sectional sizes within such limits and similarly propelled through such passage.

25. Apparatus for simultaneously thermo-chemically conditioning all four longitudinal surfaces of each of a succession of elongated metal bodies, all of such bodies being of rectangular cross-section but some of such bodies having cross-sectional sizes which differ within wide limits from the cross-sectional sizes of others of such bodies, such apparatus comprising, in combination, a group of four blowpipe nozzle means having shoes respectively forming the four sides of the border of a rectangular passage, said nozzle means being constructed and arranged to simultaneously discharge wide streams of surface conditioning medium against such four surfaces along a zone on and extending entirely around the rectangular periphery of a metal body propelled through said rectangular passage and engaged by said shoes, at least one of said nozzle means including the shoe thereof, constituting one of said four sides, being adjustable relatively to the other nozzle means and shoes of said group to change the cross-sectional size of said rectangular passage within such limits; adjusting means for changing the position of at least one of said nozzle means and the shoe thereof, relatively to the other nozzle means and shoes of said group to form any selected one of a plurality of rectangular passages of different cross-sectional sizes within said limits and thereby arrange said group of nozzle means to simultaneously dis-

charge wide streams of such medium against the four longitudinal surfaces of any selected one of a plurality of metal bodies of different cross-sectional sizes within such limits and similarly propelled through such passage; and movable supporting means for said group of nozzle means and the shoes thereof, said supporting means being freely movable in any direction in a plane substantially perpendicular to the direction of propulsion of such metal bodies, whereby warps, twists and other irregular portions along a metal body propelled through such passage in engagement with such shoes will automatically actuate such supporting means to maintain the positions of such nozzle means substantially uniform relatively to said longitudinal surfaces throughout substantially the entire length of such surfaces.

26. Apparatus for simultaneously thermodynamically conditioning all four longitudinal surfaces of each of a succession of elongated ferrous metal, all of such bodies being of rectangular cross-section but the cross-sectional sizes of some of such bodies differing considerably and within wide limits from the cross-sectional sizes of others of such bodies, such apparatus comprising, in combination, a group of four blowpipe nozzle means respectively forming the four sides of the border of a rectangular passage and constructed and arranged to simultaneously discharge wide

streams of oxidizing gas against such four surfaces along a zone on and extending entirely around the rectangular periphery of a metal body propelled through said rectangular passage, at least one of said nozzle means being adjustable relatively to the other nozzle means of said group to change the cross-sectional size of said rectangular passage within such limits; adjusting means for changing the position of at least one of said nozzle means relatively to the other nozzle means of said group to form any selected one of a plurality of rectangular passages of different cross-sectional sizes within said limits and thereby arrange said group of nozzle means to simultaneously discharge wide gas streams against the four longitudinal surfaces of any selected one of a plurality of metal bodies of different cross-sectional sizes within such limits and similarly propelled through such passage; and means operable to change the effective widths of at least two of such gas streams to correlate the widths of all four of said gas streams to the cross-sectional dimensions of such selected passage and to the cross-sectional size of the metal body undergoing conditioning.
